CLAIM

I claim the ornamental design for an herb keeper with lifting insert, as shown and described.

DESCRIPTION

FIG. 1 is a front elevational view of an herb keeper with lifting insert showing my new design, the rear, left, and right side elevational views being identical thereof;

FIG. 2 is a top plan view thereof;

FIG. 3 is a bottom plan view thereof;

FIG. 4 is a front elevational view of the herb keeper with lifting insert shown in FIG. 1 with the outer, lid and base of the herb keeper with lifting insert removed for ease of illustration;

FIG. 5 is a left side elevational view thereof; the right side elevational view being an identical mirror image thereof;

FIG. 6 is a top plan view thereof;

FIG. 7 is a bottom plan view thereof;

FIG. 8 is a bottom perspective view thereof; and,

FIG. 9 is an exploded perspective view of the herb keeper with lifting insert shown in FIG. 1 thereof.

The broken lines shown in the figures depict portions of the herb keeper with lifting insert that form no part of the claimed design.
